UNITED STATES PATENT OFFICE.

JOHN BOYD DUNLOP AND JOHN BOYD DUNLOP, JR., OF DUBLIN, IRELAND

CARBURETER FOR EXPLOSIVE-ENGINES.

No. 831,547.

Specification of Letters Patent.

Patented Sept. 25, 1906.

Application filed June 22, 1903. Serial No. 162,623.

To all whom it may concern:

Be it known that we, JOHN BOYD DUNLOP and JOHN BOYD DUNLOP, Jr., subjects of the King of England, residing at Dublin, Ireland, 5 have invented certain new and useful Improvements in Carbureters for Explosive-Engines, of which the following is a specification.

This invention relates to carbureters for 10 internal-combustion engines, and refers chiefly, though not exclusively, to carbureters intended for use on motor-vehicles.

The invention has for its chief object to so 15 construct the carbureter that it will maintain a correct and uniform mixture which will not be affected by either altering the opening of the throttle or changing the speed of the engine.

With carbureters in general use the 20 strength or composition of the mixture varies with the speed of the engine, the quantity of petrol or other fuel sucked into the engine at each stroke being small in proportion to the air when the engine is running slowly and the 25 throttle partially closed, whereas when the engine is running fast and the throttle fully open the quantity of petrol is large in proportion to the air. According to the present invention these objectionable features are 30 obviated, and when the mixture has once been adjusted the proportions thereof remain constant for all speeds of the engine and at all degrees of throttle-opening. In order to accomplish this, there is disposed in the fuel- 35 duct or spray-tube, which communicates with the float or constant-level chamber and with the mixing-chamber, one or more baffles which impede the flow of petrol more or less, according as the speed of the engine is high 40 or low. Consequently as the suction of the piston is increased or decreased the obstructive action of the baffles increases or decreases in a corresponding degree, and thus the relative proportions of air and petrol are 45 kept uniform under all conditions.

In place of or in addition to regulating the flow of petrol, as above described, the supply of air may be adjusted and regulated by means of an adjustable gate-valve or its 50 equivalent, preferably in the form of a flat spring or other plate, which can be acted upon by the suction to open to a greater or less extent as the suction increases or decreases.

55 With reference to the accompanying drawing, in which is shown a preferred construc-

tion of the apparatus suitable for use in a motor-vehicle, A is the float-chamber, in which is disposed a cork or other float A'.

B is the baffle situated in the fuel-duct or 60 spray-tube C.

D is the mixing-chamber, E the air-supply tube, and F a gate-valve or spring-plate adjustably secured therein, and G is the conduit or mixture-pipe leading to the engine cylinder 65 or cylinders.

The fuel-duct C is inclined, as shown in the drawing, and is provided with two gaps or openings C' and C'', of which the gap C' communicates with the lower part of the float-chamber A and the other enters the mixing or vaporizing chamber D at an angle to insure the rapid mixing of the air and petrol. In the upper end of the fuel-duct C is disposed an adjustable screw H, which engages 70 with a corresponding internal screw-thread in the tube and is provided with a knob or handle H', by which a jet or spray nozzle C' in the tube C can be adjusted, so as to regulate the amount of petrol passing into the 75 mixing-chamber at each operation. The tube C is extended down below the base of the float-chamber and is provided with a screw-cap C'', by removing which the petrol in the float-chamber can be run off, if de- 80 sired.

The baffle for impeding the passage of the petrol from the float-chamber to the vaporizing-chamber is conveniently disposed in the feed-tube between the two gaps C' and C'' 85 and may consist of cups or plates, ridges or grooves, the cups or plates being perforated, if desired, or spaces may be left between the edges of each plate or cup and the sides of the passage in the tube. In all cases it is preferred that the free edges of the baffles should be inclined and project against the stream of fuel, so as to break it up into small eddies or currents and prevent more effectually the excessive flow of petrol when the engine is running fast. In its preferred form, as shown in the drawing, the baffle consists of a piece of wire or thin rod B, having undercut or saw teeth B', and the baffle is placed in the tube in such a manner that it can readily be removed when desired for cleansing and other purposes.

As stated above, the function of the baffle B' is to produce a series of eddies or return-currents in the stream of petrol passing through the feed-tube C, and the resistance to the flow of petrol is due to the collisions

between such eddies or return-currents and the main stream. It is clear that the strength or power of such eddies depends upon the force with which the stream of petrol impinges on the stepped face of the baffle B' and that the said eddies will have a much greater resisting effect when the flow of petrol is rapid than when such flow is slow. When the motor is running at low speed, the flow of petrol through the feed-tube is so slow that the very slight eddies or return-currents set up by the baffle-plate offer practically no resistance to the flow, and, in fact, the baffle under such conditions hardly creates any such eddies. However, as the suction of the motor is increased, and consequently the movement of petrol becomes more rapid, the force with which the latter strikes the baffle produces such eddies, which increase in strength with any acceleration of the flow of petrol and which tend to resist or hinder such flow in direct proportion to the rate of increase of the initial flow thereof.

We prefer to adjust and regulate the flow of petrol by the means above described; but in place of or in addition to regulating the flow of petrol we may adjust and regulate the quantity of air drawn in at each operation. For this purpose a spring-plate F is disposed 25 in the air-supply tube E, to which it is connected by studs, rivets, or in any other convenient manner. The plate F is adjusted in position by a set-screw E', so that by causing the plate to extend a greater or less extent 30 across the pipe E the requisite quantity of air required to give a correct mixture may be obtained. The plate is acted upon by the inrush of air and opens to a greater or less extent as the suction of the piston in the engine-cylinder increases or diminishes, and thus the air and petrol are kept in correct proportions irrespective of the varying speed of the engine and the varying degree of opening of the throttle-valve. It will be 35 noticed that the regulation above described is effected entirely automatically and without any mechanical connection to the baffle within the spray-pipe or fuel-duct—that is, the present invention does not require any 40 such mechanical means as a lever or rod for varying the position of the device by which the supply of fuel to the mixing-chamber is regulated. The plate F may be placed anywhere between the air-inlet and jet or spray 45 nozzle.

Petrol or other fuel is admitted to the float-chamber A by a pipe or tube A², and the supply is controlled by a cork or other float A', which is guided in the chamber by means of a 50 spindle A³, and the upper end of the spindle is adapted to fit in a valve-seating A⁴ on the inlet-pipe, so that the quantity of fuel in the chamber remains constant.

The mixture is led from the mixing or 55 vaporizing chamber D by the pipe G, which

communicates by suitable pipes or conduits with the cylinder or cylinders of the engine.

What we claim as our invention, and desire to secure by Letters Patent, is—

1. In a spray-carbureter, the combination 70 with a float-chamber and a mixing-chamber, of a fuel-pipe between the chambers and having a nozzle at the end opening into the mixing-chamber, and a baffle in the fuel-pipe for automatically regulating without adjustment the flow of fuel into the mixing-chamber relatively to the quantity of air drawn into that chamber and maintaining the mixture in constant proportions independently of the speed of the engine and for all degrees 75 of opening of the throttle.

2. In a spray-carbureter, the combination 80 with a fuel-chamber and a mixing-chamber, of a fixed baffle within the fuel pipe or passage between the fuel and mixing-chambers 85 for automatically regulating the flow of the fuel into the mixing-chamber relatively to the quantity of air drawn into that chamber and automatically maintaining the mixture in constant proportions independently of the 90 speed of the engine and for all degrees of opening of the throttle.

3. In a spray-carbureter, the combination 95 with a mixing-chamber having a suitable air-inlet, and a duct for supplying hydrocarbon to said chamber, of means for regulating the admission of air to said chamber, and means within said duct for regulating the supply of hydrocarbon to said chamber, said air and hydrocarbon regulating means being independently actuated by suction through the 100 mixing-chamber.

4. In a spray-carbureter, the combination 105 with a hydrocarbon-chamber and a mixing-chamber, of means arranged between said chambers for retarding the flow of hydrocarbon into the mixing-chamber and adapted to act with a force varying with variations in the rapidity of movement of the hydrocarbon.

5. In a spray-carbureter, the combination 110 with a hydrocarbon-chamber and a mixing-chamber, of means arranged between said chambers for retarding the flow of hydrocarbon into the mixing-chamber and adapted to act with increasing force as the movement of the hydrocarbon is accelerated.

6. In a spray-carbureter, the combination 115 with a hydrocarbon-chamber and a mixing-chamber, of means arranged wholly within a duct intermediate of said chambers for retarding the flow of hydrocarbon into the mixing-chamber and adapted to act with a force proportionate to the rapidity of movement of the hydrocarbon through such duct.

7. In a spray-carbureter, the combination 120 with a float or fuel-supply chamber and a vaporizing or mixture chamber, of a fuel-conduit between the chambers, a nozzle at the inlet to the mixing-chamber, and a baffle or- 125

ranged entirely within the conduit between said nozzle and the fuel-chamber and acting with a force depending on the rapidity of movement of the fuel through said conduit, substantially as and for the purpose described.

8. In a spray-carbureter the combination with a float-chamber and a vaporizing-chamber, of an inclined fuel-pipe communicating with both chambers, a rod disposed in the pipe and having notches or serrations directed against the stream of fuel for the purpose of regulating the flow of fuel into the mixing-chamber thereby causing the strength of the mixture to remain constant for all speeds of the engine and at all degrees of opening of the throttle.

9. In a spray-carbureter the combination with a float-chamber and a vaporizing-chamber, of an inclined fuel-pipe having a gap communicating with the float-chamber and another gap communicating with the mixing-chamber, a fuel-nozzle in the pipe adjacent to the second gap, means for controlling the nozzle, a baffle in the pipe having free edges inclined against the stream of fuel, an air-pipe and means in the air-pipe for regulating the quantity of air drawn into the mixing-chamber at each operation substantially as and for the purpose described.

10. In a spray-carbureter the combination with a float-chamber and a vaporizing-chamber, of an inclined fuel-pipe having a gap communicating with the float-chamber and another gap communicating with the mixing-chamber, a fuel-nozzle in the pipe adjacent to the second gap, means for controlling the nozzle, a baffle in the pipe having free edges inclined against the stream of fuel, an air-pipe and means in the air-pipe for regulating the quantity of air drawn into the mixing-chamber at each operation substantially as and for the purpose described.

air-pipe, an adjustable plate in the air-pipe 40 for regulating the quantity of air drawn into the mixing-chamber at each operation and means for adjusting the plate substantially as described.

11. In a spray-carbureter the combination 45 with a float-chamber and a vaporizing-chamber, of an inclined fuel-pipe having a gap communicating with the float-chamber and another gap communicating with the mixing-chamber, a fuel-nozzle in the pipe adjacent to the second gap, means for controlling the nozzle, a baffle in the pipe having free edges inclined against the stream of fuel, an air-pipe, a spring-plate in the air-pipe and a screw for adjusting the position of the plate 55 substantially as and for the purpose described.

12. In a spray-carbureter the combination with a float-chamber and a vaporizing-chamber of an inclined fuel-pipe communicating 60 by separate gaps with the float-chamber and the vaporizing-chamber, a nozzle in the pipe, a regulating-screw for the nozzle, a baffle in the tube having teeth inclined against the stream of petrol, a screw-cap closing the 65 lower end of the fuel-pipe, an air-pipe, a spring-plate disposed in the air-pipe and a screw for adjusting the position of the plate substantially as and for the purpose described.

In testimony whereof we have signed our names to this specification in the presence of two subscribing witnesses.
